UNITED STATES PATENT OFFICE.

CHARLES H. MERWARTH, OF SOUTH BETHLEHEM, AND FREDERICK CONLIN, OF BETHLEHEM, PENNSYLVANIA, ASSIGNORS TO THE MERWARTH METALLIC GASKET COMPANY, OF SOUTH BETHLEHEM, PENNSYLVANIA.

DESIGN FOR A GASKET OR PACKING FOR JOINTS OF PIPES OR OTHER APPARATUS.

SPECIFICATION forming part of Design No. 33,782, dated December 25, 1900.

Application filed December 3, 1900. Serial No. 38,574. Term of patent 14 years.

To all whom it may concern:

Be it known that we, CHARLES H. MERWARTH, of South Bethlehem, and FREDERICK CONLIN, of Bethlehem, in the county of Northampton, and in the State of Pennsylvania, have invented and produced a certain new and original Design for a Gasket or Packing for the Joints of Pipes or other Apparatus; and we do hereby declare that the following is a full, clear, and exact description thereof, reference being had to the accompanying drawings, in which—

Figure 1 is a plan view of a gasket or packing, showing our new design; and Fig. 2 is a cross-section of the same.

Letters of like name and kind refer to like parts in both figures.

The object of our invention is to provide a design for gaskets or packing for the joints of pipe or other apparatus; and to this end said invention consists in the design for a gasket or packing, substantially as herein shown and described.

The leading feature of our design consists in the shape or configuration, which comprises an inner ring A, an outer ring B, and an intermediate ring C. 25

Having thus described our invention, what we claim is—

The design for a gasket or packing for the joints of pipe or other apparatus, substantially as and for the purpose described. 30

In testimony that we claim the foregoing we have hereunto set our hands this 24th day of September, 1900.

CHARLES H. MERWARTH.
FREDK. CONLIN.
